(57) **CLAIM**

I claim the ornamental design for a battery operated dental flosser, as shown and described.

DESCRIPTION

FIG. 1 is a perspective view of my ornamental battery operated dental flosser;

FIG. 2 is a top plan view of the battery operated dental flosser;

FIG. 3 is a bottom plan view of battery operated dental flosser;

FIG. 4 is a side elevation of the battery operated dental flosser as seen from the right side of FIG. 1;

FIG. 5 is a side elevation of the battery operated dental flosser as seen from the left side of FIG. 1;

FIG. 6 is a front elevational view thereof taken from the front of FIG. 1; and,

FIG. 7 is a rear elevational view thereof taken from the rear of FIG. 1.
